UNITED STATES PATENT OFFICE

GEORGE GLASS, SR., OF ERIE, PENNSYLVANIA

SELF-SERVING TRAY

Application filed August 4, 1925. Serial No. 48,103.

The invention relates to an appliance to be set upon a dining table and to hold various articles of food, condiments, etc., for use by the diners, and has for its object the provision 5 of a device of this character comprising a novel construction of revoluble platform including a novel bearing structure therefor, the device being so constructed that it may be readily seated upon and removed from the 10 dining table.

The construction and operation of the invention as well as its advantages will be described in detail hereinafter and the construction will be found illustrated in the accompanying drawings in which—

Figure 1 is a side view of a device showing it seated on a table top;

Figure 2 a bottom plan view of the self-serving tray;

Figure 3 a transverse sectional view of the tray taken on a plane indicated by the line 3—3 of Figure 2, and

Figure 4 a plan view of the separator disk.

In the drawings similar reference characters will be used to designate corresponding parts throughout the several views.

The improved self-serving tray comprises a base 1 having a downwardly extending flange 2 on its edge to raise the base above the 30 level of the table top A, and a central up-standing boss 3. The platform 4 of the self-serving tray is revolvably mounted on the boss 3 by means of a pivot pin or bolt 5 secured centrally through the boss 3, it being understood that the platform is designed to hold 35 the articles of food, condiments, etc., for the use of the diners.

A separator disk 6 is interposed between the base 1 and platform 4, and is provided 40 with a plurality of openings 7 adjacent the outer edge of the disk, 8 indicating downwardly extending flanges surrounding the openings 7. 9 indicates spherical bearing members contained within the openings 7 and 45 engaging the flanges 8 and the contiguous surfaces of the base 1 and platform 4 and serve to prevent frictional contact between said contiguous surfaces. The central portion of the disk 6 is provided with an offset 10 50 to admit of the back portion of the disk be-

ing located practically midway between the contiguous surfaces of the platform 4 and the base 1, said disk being rotatably mounted around the pivot pin 5.

In use, it will be apparent that the device 55 may be readily seated upon the dining table when it is desired to put it into use and may be as readily removed therefrom, and when in use, the diners may readily secure any article of food or condiment that may be on the 60 platform 4 without disturbing his neighbor diner.

What is claimed is:—

A self-serving tray for tables, comprising a base adapted to seat on a table, an upstanding 65 spherical boss in said base and recessed on its under side, a disk formed of sheet metal and having an offset portion centrally thereof seated on said boss, said disk provided with a plurality of openings, anti-friction bearing members in said openings and bearing on the base, the sheet metal forming the disk being bent to form a flange around each of said openings to enclose the anti-friction bearings, a platform supported on said offset portion and said bearing members, and a securing member engaging through alined openings in the platform, the offset portion and the boss and permitting rotation of the platform and disk relatively to the base. 70 75 80

In testimony whereof I affix my signature.
